UNITED STATES PATENT OFFICE.

FRANK CASPER, OF CLEVELAND, OHIO, ASSIGNOR OF ONE-THIRD TO WALTER J. PAINE,
OF MAPLE HEIGHTS VILLAGE, OHIO.

GRIPPER FOR PRINTING-PRESSES.

1,326,390.

Specification of Letters Patent.

Patented Dec. 30, 1919.

Application filed April 12, 1919. Serial No. 289,636.

To all whom it may concern:

Be it known that I, FRANK CASPER, a citizen of the United States, residing at Cleveland, in the county of Cuyahoga and 5 State of Ohio, have invented certain new and useful Improvements in Grippers for Printing-Presses, of which the following is a specification.

This invention relates to grippers for 10 printing presses, its object being to provide an improved auxiliary attachment to be applied to the grippers provided on presses of the bed and platen type.

It has long been a common source of 15 trouble to printers in making the sheets of paper lie flat upon the platen of the press, the grippers ordinarily supplied on the press engaging the sides of the paper only, and, due to the movement of the press and the 20 suction created when leaving the surface of the type the paper moves, frequently result in poor copies. Various methods have been employed, such as the stretching of strings or rubber bands but this is a make-shift 25 arrangement whose period of effectiveness is of short duration.

The objects of the device as illustrated 30 consists in the provision of means which can be readily adjusted to suit different work, the provision of a device which may be simple and efficient in operation, cheap of 35 construction and one which, after being adjusted vertically along the gripper and to the proper position, will not become dis- placed due to the vibrations to which it is subjected.

Figure 1 of the drawing is a perspective view of the device;

Fig. 2 is a sectional detail on the line 40 2—2 of Fig. 3; and

Fig. 3 is a sectional detail on the line 3—3 of Fig. 2.

Referring to the drawings in which like numerals designate like parts, the device 45 consists of a gripper 1 properly secured to the gripper bar of the press, the method of securing same to the press being common and well known to those familiar with the art, and illustration is not deemed necessary. Along one of the edges of the afore-

mentioned gripper a plurality of notches 2 are provided for a purpose to be described.

The attachment comprises a finger 3 formed as an extension of a box like frame or structure indicated generally at 4, this 55 consists in a stamping formed with a bottom wall 5 which has its outer surface on the same plane with that of the finger 3. Thus it will be seen that the entire surface lies flat upon the paper holding the same 60 tightly against the platen at all times. Sides 6 and 7 are formed at right angles to the bottom, the side 6 having its end bent at right angles to the bottom to form a top portion 8 extending the full length and substantially midway of the width of the structure. The side 7 is split a short distance from each end, thus forming the extension or finger 3, and the remaining portions of the side are shortened and also bent at right 70 angles to form the other half of the top portion 8^a opposite to the top portion 8.

A tension spring 9 is secured by means of rivets 10 to the lower portion of the side 7 and its lower end is formed in such a 75 manner as to provide a detent 11 which engages the notches 2 of the gripper 1. The end of the spring remote from the side 7 is curled upon itself, thereby providing an operating portion 12 to lift the detent 11 80 from the notches when the device is to be adjusted.

I claim—

A notched gripper provided with a frame 85 slideable along the same, said frame comprising a rear wall with a finger projecting from one edge thereof and having flanges at opposite edges thereof overlapping the front face of the gripper, and a spring secured to one of said flanges and extending 90 downwardly therefrom and parallel to the notched edge of the gripper and bent to form a detent engageable in the notches.

In testimony whereof, I do affix my signature in presence of two witnesses.

FRANK CASPER.
